UNITED STATES PATENT OFFICE.

THOMAS JOHN WOODWARD, OF BIRMINGHAM, ENGLAND, ASSIGNOR TO CHANCE BROTHERS AND CO., LIMITED, OF WEST SMETHWICK, NEAR BIRMINGHAM, ENGLAND.

DESIGN FOR PLATE-GLASS.

SPECIFICATION forming part of Design No. 34,847, dated July 23, 1901.

Application filed June 17, 1901. Serial No. 64,962. Term of patent 14 years.

To all whom it may concern:

Be it known that I, THOMAS JOHN WOODWARD, a subject of the King of Great Britain, residing at No. 50 Cherry street, Birmingham, England, have invented and produced a new and original Design for Plate-Glass, of which the following is a specification.

The drawing represents a face view of a piece of plate-glass ornamented with my design and also a cross-section of the same, taken on the dotted line *xx*.

The design, which is in low relief or intaglio, as shown by the section, is composed of a daisy-pattern *a* on a ground of berries or hemispherical projections *b*, alternating with a pattern composed of four anthemions *c c c c*, the points of which meet in the center of the

said anthemion-pattern, the daisy and anthemion patterns being separated by scrolls *d d d d*, having volute-like ends *e*, from which ²⁰ the anthemions *c* spring.

Having described my invention, what I claim as new, and desire to secure by Letters Patent, is—

The design for plate-glass as herein shown ²⁵ and described.

In testimony whereof I have hereunto set my hand in presence of two subscribing witnesses.

THOMAS JOHN WOODWARD.

Witnesses:

RICHARD SKERRETT,
ARTHUR JOHN POWELL.
